STRAP AND BUCKLE FASTENING

Frank Brighten, London, England

Application February 5, 1938, Serial No. 189,004
In Great Britain September 13, 1937

1 Claim. (Cl. 24—266)

This invention relates to a stop device for use on straps used in strap and buckle attachments of the kind where a strap is threaded through a prongless buckle and held by friction.

5 One example is the buckle on the side of a bathing cap which is attached to the cap generally by a press-stud fastener, the socket part of which is made on the middle bar of the buckle, and the strap is a rubber chin strap. The invention is not limited to this example. In this kind of attachment, the strap is threaded through the slot on one side of the buckle (between the frame and the middle bar) passed over the bar, and returned through the slot on the other side 10 of the buckle. The primary object of the present stop device is to avoid the accidental withdrawal of the strap from the buckle, or any loosening sliding movement, a defect to which this kind of fastening is liable, especially when 15 the strap is of rubber and has become wet. A further object is to provide means which not only prevent this accidental movement of the strap in the buckle, but will not impede the action of threading the strap when making the fastening.

20 According to the invention the strap, at or near the end intended for threading through the buckle and on that face which lies against the bar of the buckle, is provided with a flat projection which forms a point directed towards the strap end and an abutment ridge at the opposite end which acts as a retaining stop preventing accidental withdrawal of the strap through the buckle.

An embodiment of the invention is illustrated 25 by way of example in the accompanying drawing which shows the application to the strap of a bathing cap. In the said drawing:

Figure 1 is a side view showing the strap secured in position through its buckle which is fixed (according to the example) to a bathing cap;

Figure 2 is a perspective view to a larger scale 30 of the end of the strap threaded through the buckle; and

Figure 3 is an edge view of Figure 2.

Referring to the drawing, the strap 1 is provided with a flat projection 2 on one of its faces (i. e. the one which, in use, lies against the bar

3 of the buckle 4), said projection being located at or near the end of the strap intended for threading through the buckle. The projection 2 has a point 5 directed towards the strap end and an abutment ridge 6 at the opposite end. 5 The pointed end 5 may be thinned off so that the flat projection 2 is wedge-shaped merging into the surface of the strap as more clearly seen in Figures 2 and 3.

The projection 2 may be triangular shaped 10 (not illustrated) with the base of the triangle disposed transversely across the strap to form the abutment ridge 6, and the apex pointing longitudinally towards the end of the strap similar to the direction of the point 5. 15

In the form illustrated, the projection is triangular but with its base outwardly curved at 6, e. g. semi-circular. This may, however, be a flat arc, or the contour given may be pear-shaped with the point of the pear lying in the 20 direction of the point 5.

Such a projection may be moulded integrally with the strap or may be attached thereto.

In use the pointed end 5 of the projection 2 facilitates the threading of the strap through 25 the buckle 4 whilst the abutment or wide end 6 prevents the accidental withdrawal. By giving this abutment edge the curved configuration illustrated the action of deliberately detaching the strap is not greatly hindered by the abut- 30 ment edge 6.

I claim:

In a strap and buckle attachment for bathing caps, a flat prongless buckle having strap receiving slots, a flexible strap having an integral stop device thereon near the leading end thereof, said device consisting of a substantially flat compressible projection formed on one face of the strap, said projection being thinned off in the direction of its length toward the leading end 40 of the strap and merging into the surface of the strap to facilitate its being compressed and threaded through the slots of the buckle, and the end of the projection opposite the leading end of the strap providing an abutment ridge 45 for engaging an edge of one of the slots in the buckle.

FRANK BRIGHTEN.
